MOLDED PLASTIC CARTON

Neil S. Waterman, Stamford, Conn., assignor to McCormick & Company, Incorporated, Baltimore, Md., a corporation of Delaware

Filed Jan. 30, 1963, Ser. No. 73,379

Term of patent 14 years

(Cl. D58—12.6)

Fig. 1.

Fig. 2.

Fig. 3.

Fig. 4.

Fig. 5.

Fig. 6.

FIGURE 1 is a front elevation of a molded plastic carton embodying my new design;

FIGURE 2 is an end elevation of the same;

FIGURE 3 is a bottom plan view;

FIGURE 4 is a top plan view;

FIGURE 5 is a longitudinal, vertical sectional view on line 5—5 of FIGURE 2, and

FIGURE 6 is a vertical transverse sectional view on line 6—6 of FIGURE 4.

The rear elevation not shown is like the front elevation shown in FIGURE 1.

The characteristic features of the design of the molded plastic carton disclosed reside in the slightly downwardly tapering relation of the side and end walls of the lower section and the more pronounced upwardly tapering relation of the side and end walls of the upper section, with

the walls of the upper section having less vertical height than the walls of the lower section.

I claim:

The ornamental design for a molded plastic carton, as shown and described.
